UNITED STATES PATENT OFFICE.

JOHN FRITZ, OF NEW BEDFORD, MASSACHUSETTS.

DESIGN FOR A TOY.

657,038.

Specification for Design.

Patented Feb. 1, 1921.

Application filed July 31, 1920. Serial No. 400,553. Term of patent 7 years.

To all whom it may concern:

Be it known that I, JOHN FRITZ, a citizen of the United States, and a resident of New Bedford, in the county of Bristol and State of Massachusetts, have invented a new, original, and ornamental Design for Toys, of which the following is a specification.

Reference is to be had to the accompanying drawing, in which the figure is a perspective view of a toy showing my improved design.

I claim—

The ornamental design for a toy as shown.

JOHN FRITZ.
